UNITED STATES PATENT OFFICE.

ALBERT HAYES, OF WASHINGTON, DISTRICT OF COLUMBIA, ASSIGNOR TO
NICHOLAS AUTH, OF WASHINGTON, DISTRICT OF COLUMBIA.

BRANDING APPARATUS.

SPECIFICATION forming part of Letters Patent No. 728,710, dated May 19, 1903.

Application filed December 5, 1902. Serial No. 134,024. (No model.)

To all whom it may concern:

Be it known that I, ALBERT HAYES, a citizen of the United States, residing at Washington, District of Columbia, have invented certain new and useful Improvements in Branding Apparatus; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in branding appliances and heating apparatus; and it consists in the provision of an oil-atomizer communicating with a mixing-chamber, where the vaporized oil and steam are thoroughly commingled before being ignited at the burner, suitable means being provided to break up and equally distribute the flame, so that the branding-surfaces will be uniformly heated.

The invention consists, further, in various details of construction and combinations of parts, which will be hereinafter fully described and then specifically defined in the appended claims.

The invention is illustrated in the accompanying drawings, which, with the letters of reference marked thereon, form a part of this application, and in which drawings—

Figure 1 is a perspective view of my improved branding apparatus shown as held adjacent to a table. Fig. 2 is a central vertical section through the branding apparatus with the oil-tank shown in elevation, and Fig. 3 is a sectional view through the heating-chamber on which the branding-plates are mounted.

Reference now being had to the details of the drawings by letter, A designates a fuel-reservoir having a central tube A', passing through the top of said reservoir and opening at a point adjacent to the lower end of the reservoir, and a valve B is positioned in said pipe, whereby the supply of oil being fed from said tube may be regulated. Said reservoir is provided with a suitable gage C and a filling-aperture D and a valve E, to which an air-pipe from a force-pump may be connected to apply a suitable pressure upon the surface

of the oil to cause the same to flow through the mixing-chamber and burner. Mounted on the upper end of said tubing A' is a boxing F, which is chambered out, and journaled in the walls of said boxing is a shaft h, on which is mounted a pinion-wheel H, and a suitable hand-wheel h' is fastened to the shaft h, whereby the pinion may be rotated in one direction or the other.

G designates an oil-cylinder having a circumferential flange G' adjacent to one end, and said cylinder is held to the boxing F by means of a nut I, which fits over a contracted threaded portion of said boxing, whereby the inner wall of said cylinder is continuous with the chambered portion of the boxing into which oil enters from the tubing A'. A portion of the circumference of said oil-cylinder G is threaded, as at g, to receive the mixing-chamber K, which has one end apertured and provided with screw-threads to engage the threads g. A needle-valve L is mounted horizontally in said oil-cylinder, mixing-chamber, and boxing, and has rack-teeth L' adjacent to one end adapted to mesh with said pinion-wheel H and is provided with two conical valves N and N', the former of which is adapted to control the passage of vaporized oil through the port O in the tapering end of the oil-cylinder, while the valve N' is designed to control the passage of the vaporized oil and steam which passes through the port n at the apex of said mixing-chamber. A pipe R leads into said mixing-chamber and through which steam is allowed to enter the chamber from any source of supply.

Mounted upon a bracket-arm S, which is fastened to the oil-reservoir, is a chamber T, having an aperture in its circumference, through which the tapering end of said mixing-chamber passes, as shown clearly in Fig. 2 of the drawings. Said chamber has a perforated bottom T' and a top T'', supporting branding-plates W, there being two of these plates shown in the drawings; but any number may be utilized, if desired. Secured to said top T'' and projecting downward in the chamber T and arranged preferably in circular series are the rods J, which are provided for the purpose of breaking up the flame and distributing the heat uniformly

within the chamber T. These rods also serve as means for retaining heat and assisting in the combustion of the vaporized fuel as it issues through the port controlled by the 5 valve N'.

From the foregoing it will be observed that by the provision of apparatus embodying my invention the oil and steam in the mixing-chamber will become heated by proximity of 10 the latter to the heating-chamber, as said mixing-chamber extends into the heating-chamber, thereby causing a rapid combustion as the spray issues from the exit end of the mixing-chamber. Hams or other articles desired to be branded may be placed upon the 15 branding-plates and the apparatus may be positioned adjacent to a table, as illustrated in Fig. 1 of the drawings, for convenience in use. The branding-plates will be highly heated by the intense heat generated by means 20 of the burner apparatus, in which the oil is thoroughly atomized and mixed with the steam prior to its being forced out of the mixing-chamber and ignited at the burner end 25 of the mixing-chamber, and by means of the valves positioned within the oil-cylinder and mixing-chamber the supply of fuel being fed to the burner may be readily adjusted, thereby insuring any degree of heat desired. 30 Having thus fully described my invention, what I claim as new, and desire to secure by Letters Patent, is—

1. A branding apparatus comprising a fuel reservoir, an oil-cylinder communicating with 35 said reservoir through a valve-regulated passage-way, a heating-chamber, a mixing-chamber having a tapering end entering the latter and communicating therewith and also with said oil-cylinder, a steam-inlet pipe communicating with said mixing-chamber, a shaft 40 having valves adapted to control the exit-

ports of said mixing-chamber and cylinder, a rack and pinion for moving said shaft to simultaneously open and close said valves, and branding-plates supported upon said heating-chamber, as set forth. 45

2. A branding apparatus comprising an oil-reservoir, a bracket-arm supported thereon, a heating-chamber mounted on said arm, branding-plates supported upon the heating-chamber, and circular series of deflecting-rods projecting down from the top of said chamber, a mixing-chamber communicating with said heating-chamber, an oil-cylinder with pipe connection with said reservoir and extending 50 into the mixing-chamber and having a tapering and apertured end communicating with the mixing-chamber, and valves regulating the exit-ports in said cylinder and mixing-chamber, as set forth. 55

3. A branding apparatus comprising an oil-reservoir, a valve-regulated pipe leading therein, a boxing mounted on said tubing, a shaft journaled in said boxing and having a pinion-wheel thereon, an oil-cylinder held to 60 said boxing, a mixing-chamber having threaded connection with the circumference of the oil-cylinder, a heating-chamber communicating through the mixing-chamber with said cylinder, a steam-inlet pipe communicating 65 with said mixing-chamber, valves communicating with said ports in said cylinder and mixing-chamber, and rack-teeth on the stem of the valves in mesh with said pinion, and branding-plates mounted upon the heating-chamber, as shown and described. 70

In testimony whereof I hereunto affix my signature in presence of two witnesses.

ALBERT HAYES.
